UNITED STATES PATENT OFFICE.

FRANCIS B. RILEY, OF NEWTON HIGHLANDS, MASSACHUSETTS, ASSIGNOR TO HEYWOOD-WAKEFIELD COMPANY, OF BOSTON, MASSACHUSETTS, A CORPORATION OF MASSACHUSETTS.

FABRIC.

Application filed July 16, 1923. Serial No. 651,741.

The present invention relates to a new form of fabric and more particularly to a fabric composed of non-flaccid material such as cane, reed, twisted paper and the like.

It will be evident to those skilled in the art that fabrics composed of reed strands, or reed fabric, so called, are commonly woven with a series of spaced stakes about which are woven filler strands. The stake members 10 ordinarily have sufficient rigidity to be self-supporting and to resist distortion or bending of the fabric in one direction. This type of reed fabric, so called, is largely used in connection with the manufacture of wicker 15 furniture, baby carriages and similar articles, in some instances the fabric being woven directly upon the article and conforming closely to the exact shape of the article and in other cases the fabric being woven to 20 a regular predetermined shape other than the shape of the article and thereafter applied to the frame of the article and shaped there-over.

The purpose of the present invention is to 25 provide a new and greatly improved form of fabric which may be successfully incorporated in so called wicker furniture, baby carriages and similar articles of various types in place of the present reed fabric and which 30 from the standpoint of strength and artistic appearance presents many advantages over the present reed fabric. A further object of the present invention is to produce a new form of fabric which not only is susceptible 35 of use in all of the various ways in which reed fabric is now employed but in addition, due to its inherent strength and rigidity in all directions, may be successfully employed in a manner not possible with the present fabric.

With these and other objects in view, the 40 various features of the invention consist in certain novel features of construction, combinations and arrangements of parts herein-after described and claimed, the advantages 45 of which will be obvious to those skilled in the art from the following description.

In the accompanying drawings illustrating 50 the preferred form of the invention Figs. 1 to 3, inclusive, are respectively a plan and elevations partly in section of a conventional form of the new fabric employing round strands and stakes; Figs. 4 and 5 illustrate similar views of a fabric employing round strands with the weaving strands extending

about two of the post members; Figs. 6 to 8, 55 inclusive, are views illustrating a form of fabric produced by the employment of round post members of different diameter; Figs. 9 to 11, inclusive, are views illustrating a fabric produced by causing the weaving members 60 to pass first about two post members and thereafter about the opposite side of a single post member; Figs. 12 to 14, inclusive, illustrate a fabric produced by alternating two weaving members and two spacer members; 65 Figs. 15 to 17, inclusive, illustrate a fabric produced by the employment alternately of flat and round strands for the post members; Figs. 18 to 20, inclusive, illustrate a fabric produced through the employment of substantially flat strands; Figs. 21 and 22 illustrate 70 partially diagrammatically the manner in which either set of strands when the fabric is produced mechanically may be the warps and either set the wefts, Fig. 21 illustrating a construction in which the post members, so called, are the warps and the weaving and spacer strands the wefts, Fig. 22 illustrating a construction in which the weaving and spacer strands are the warps and the post 75 members the wefts; Figs. 23 to 29, inclusive, illustrate the new form of fabric produced in a variety of predetermined and differing shapes, in these cases the post members extending lengthwise of the shape and the 80 spacer and weaver members extending circularly about the shape; and Figs. 30 to 32, inclusive, illustrate still another form of fabric incorporating both flat and round strands in 85 a unique design.

Upon referring to the illustrated embodiment of the invention, it will be observed that the present form of fabric consists of a series of substantially parallel strands 50 upon opposite sides of which are disposed a series of stakes 52. The stakes extend at right angles 90 to the first series of strands and in the embodiment of the invention shown in Figs. 1 and 3 successive stakes 52 are disposed alternately upon opposite sides of the strands 100 50, the strands 50 serving to space and locate the stakes 52 and determine the relative positions of these. The two sets of stakes and strands are locked in assembled position by a third series of strands indicated at 54, 105 which extend substantially in the direction of the strands 50 and pass in and out about opposite sides of the stakes 52. The strands

54 assume a wavy contour, as indicated clearly in Fig. 2, and lock the two sets of stakes and strands in assembled position. As will be evident from an inspection of the drawings, the two sets of strands and stakes 50 and 52 extend substantially straight with respect to the plane of the fabric, except as they may be bent slightly to conform to the contour of an article in which the fabric is embodied. 10 The incorporation of these two sets of substantially straight strands extending both lengthwise and transversely of the fabric permits the employment, if so desired, of substantially unyielding strands which impart 15 strength and rigidity to the fabric in all directions. The weaving strands extending in and out on opposite sides of the straight strands impart a characteristic and desirable appearance to the fabric and produce a fabric which lends itself admirably to ornamentation in a variety of ways. Furthermore, the fact that the weaving strands pass upon opposite sides of successive straight stakes which are in turn disposed upon opposite 25 sides of straight spacing strands gives a distinct thickness and body to the fabric which is not possible to obtain with fabrics previously made from material of this character.

For convenience of description, the strands 30 50 are termed "spacer strands" the stakes 52 disposed alternately upon opposite sides of the strands 50 are termed "post members" and the strands 54 serving to lock the strands 50 and 52 together are termed "weaver members". It will be evident to those skilled in the art that although the fabric shown in the accompanying drawings comprises three sets of strands, nevertheless the spacer members might be dispensed with and the post 35 members retained in different planes offset from one another by causing the post members to extend diagonally in different directions, as by having two sets of post members each set extending diagonally in a given direction, the weaver members passing about 40 opposite sides of the post members to lock the two sets of post members in assembled relation.

The present fabric is most conveniently 45 produced by assembling the spacer members and weaver members in the proper relation and forming sheds successively in the weaver members through which the post members are passed, these sheds being disposed successively above and below the spacer members.

From an inspection of the various figures of the drawings, it will be evident that by 50 causing the weaver members to pass about opposite sides of successive post members which are in turn disposed upon opposite sides of spacer members a fabric is produced having a depth equivalent to the thickness or diameter of five strands, whereas in the ordinary reed fabric, so called, the depth is equiv-

alent to the aggregate thickness or diameter of only three strands. Thus the present fabric presents a much heavier and more durable appearance than existing types of reed fabric and in addition the pronounced series of waves which are formed eliminate the tendency to a flat appearance and affords a desirable contrast with the possibility of pleasing shadow effects. 70

Figs. 4 to 20, inclusive, illustrate numerous fabrics embodying the characteristic features of the present invention. For example, Figs. 4 and 5 illustrate a fabric in which the weaver members 54 pass about the opposite sides of two post members 52, all of the strands being 80 round and of the same diameter. Figs. 6 to 8, inclusive, illustrate a fabric similar to Fig. 1, except that the post members 52 vary in diameter as indicated, each set of small post members having interposed therebetween a 85 post member of substantially larger diameter. Figs. 9 to 11, inclusive, illustrate a construction in which the weaver members 54 pass first about the same side of the two post members 52 and thereafter about the opposite side 90 of a single post member. Figs. 12 to 14, inclusive, illustrate a fabric in which the spacer members 50 and the weaving members 54 are assembled in pairs, each two pairs of spacer members being separated by a pair of weaving members and vice versa, the post members of this fabric being also of greater diameter than the weaving and spacer members. Figs. 15 to 17, inclusive, illustrate a construction in which a series of round weaver and 95 spacer members are interlocked alternately with a pair of round post members 52 and flat post members 60. Figs. 18 to 20, inclusive illustrate the fabric produced through the utilization of flat strands for the spacer, 100 weaver and post members. Fig. 21 illustrates somewhat diagrammatically the production of the new form of fabric with the post members 52 as warps and the spacer and weaver members 50 and 54 as wefts or fillers. 105 Fig. 22 illustrates diagrammatically the usual method of making the fabric in which the post members 52 are weft or filler members and the weaver and spacer members 50 and 54 are warps. Fig. 23 illustrates diagrammatically the production of a curved fabric in which the posts 52 may be arranged in non-parallel relation and have a series of weaver and spacer members 50 and 54 woven thereabout. Figs. 24 to 29, inclusive illustrate fabrics embodying the characteristic features of the invention and woven in predetermined contours. Figs. 28 and 29 illustrate somewhat diagrammatically the relative positions of the post members, spacer members and weaver members. Figs. 30 to 32 illustrate a further form of fabric embodying the features of the invention in which a series of round post members 52 alternate with flat post members 75 and a series of round spacer 115

members 50 alternate with flat spacer members 76, each flat spacer member being separated from the series of round spacer members by a single round weaver member 54.

5 Although the spacing strands have been described as straight and lying in the plane of the fabric, it will be evident to those skilled in the art that in the practical operation of producing such a fabric a relatively slight 10 distortion or bending of the spacer members may take place due to the pull exercised by the weaving members and the relatively greater rigidity of the post members extending transversely to the spacers. If the spacer 15 members have greater rigidity than the post members then the pull on the weaver members may cause a slight distortion of the post members rather than the spacers.

I claim:

20 1. A stake and strand fabric of non-flaccid material comprising a series of spaced parallel stakes positioned in two parallel spaced planes, and a plurality of closely spaced and contacting parallel strands of substantial 25 cross-section extending lengthwise of the fab-

ric with certain of the strands lying in a plane intermediate the planes of the stakes and certain of the strands extending about opposite sides of the stakes and repeatedly intersecting the planes of the stakes and the intermediate 30 plane of the strands to interweave the stakes and strands and present a distinctly undulating contour to the finished fabric.

2. A stake and strand fabric of non-flaccid 35 material comprising a series of spaced parallel stakes positioned in two parallel spaced planes, and a plurality of closely spaced and contacting parallel strands of uniform size and substantial cross-section extending lengthwise of the fabric with certain of the strands 40 lying in a plane intermediate the planes of the stakes and certain of the strands extending about opposite sides of the stakes and repeatedly intersecting the planes of the stakes and the intermediate plane of the 45 strands to interweave the stakes and strands and present a distinctly undulating contour to the finished fabric.

FRANCIS B. RILEY.
